Primary Examiner — Paula Allen Greene(74) *Attorney, Agent, or Firm* — O'Connell Law Firm;
Thomas P. O'Connell(57) **CLAIM**

We claim the ornamental design for a headset, as shown and described.

DESCRIPTION

FIG. 1 is a perspective view of a headset showing our design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof;

FIG. 7 is a bottom plan view thereof; and,

FIG. 8 is a perspective view thereof, the only difference being the unclaimed broken lines.

The broken lines depict portions of the headset that form no part of the claimed design.
